UNITED STATES PATENT OFFICE.

JEAN MARIUS GARAIX, OF CONVENT STATION, NEW JERSEY.

SUSPENSORY BANDAGE.

1,116,879.

Specification of Letters Patent.

Patented Nov. 10, 1914.

Application filed October 2, 1912. Serial No. 723,651.

To all whom it may concern:

Be it known that I, JEAN MARIUS GARAIX, of Convent Station, Morris county, New Jersey, have invented certain new and useful Improvements in Suspensory Bandages, of which the following is a specification, accompanied by drawings.

This invention relates to suspensory bandages and the primary object of the invention is to improve upon the means for supporting the suspensory, entirely at the front and solely in a vertical direction, in contradistinction to a partly vertical and partly transverse support.

15 A suspensory that is not supported solely at the front, has understraps, but understraps, at the best, are very distressing. If, on the other hand, the sustaining force is not exercised solely in a vertical direction, 20 directly above the supported parts, there is necessarily both an upward and a transverse strain or pull. But a partly transverse support means a support, the bearing point of which is at the hips, and as such is very objectionable, because in that case the pouch 25 constantly tends to get out of place, and it is in an attempt to remedy this grave defect that so many suspensors have the cumbersome addition of under-straps.

30 One preferred embodiment of the invention is shown in the accompanying drawings, in which—

Figure 1 is a side view of a pouch in process of construction; Fig. 2 is a detail view, partly broken away, of the upper portion of the pouch, showing the back at the left hand side, and the front at the right hand side, on opposite sides of the median line of the pouch; Fig. 3 is an elevation of 40 a pouch, showing the back at the left hand side and the front at the right hand side of the median line; Fig. 4 is a front view of a complete suspensory bandage, before the parts are completely adjusted, and Fig. 5 is 45 a front view of a suspensory with the parts adjusted, except for one flexible tape which needs to be drawn up and knotted.

Referring to the drawings, the pouch shown in Fig. 1 is presumed to be full size 50 for a man measuring about forty inches at the waist. The pieces M and N of suitable material as Deimels net are cut substantially according to the lines indicated in outline between the points o' , o^2 , p' and p^2 . These 55 pieces M and N are then superposed and stitched together at the dotted line, running

parallel with the edge p' , p^2 . The hem is preferably afterward pressed open, and covered with tape a from p' to p^2 . The bordering comes next, and accordingly tape b is 60 run from the point o' downward toward p' and continued to s' . This is the border which passes behind the scrotum. The tape c is also run from the point o^2 to s^2 , and this is the border which makes the front opening. 65

Referring to Fig. 2, the pieces M and N are first tucked up at the upper part, so as to reduce by a full half the respective widths o' , o^2 and s' , s^2 . The tucking is then made firmer by means of two tapes, one at o' , o^2 70 and the other at e , f , g , h . Two tapes are affixed in a similar way to the corresponding sides s' , s^2 , all as shown in Fig. 2. The sides o' , o^2 and s' , s^2 , are also connected by means of a webbing tape a^4 , b^4 , c^4 , d^4 , and three 75 loops A, B and C, also of webbing material are sewed at the places indicated in the drawing.

Fig. 2 shows substantially the exact shape the upper part of the pouch has when completed, and Fig. 3 shows the shape the whole pouch takes after it has been worn a while, and the pouch remains constantly thus, 80 without sagging, until entirely worn out.

The waist band may be described as follows: Referring to Fig. 4, the waist band is elastic in the front, that is, from hip to hip, and non-elastic in the back. The elastic portion is preferably made of two segments, one extending from the buckle, that is from 90 the point j to c' and the other from the point k to b' . The non-elastic portion is indicated by a' , a^2 , a^3 and extends as far as the point k . On each segment of the elastic band, the loops l and m are sewed, and the 95 flexible tape of which they are made, extends out several inches from under the loops. To adjust the waist band, the extremity c' is passed through the loops A, B and C and fastened by a button at button hole t , 100 which button hole is made in a short tongue or flexible tape sewed on the end b' of the elastic band. The free ends of the flexible tapes are also adjusted. Tape d' , d^2 passes first through loop A, then through loop l , 105 where it is fastened by a knot, as shown in Fig. 5. The same is done with tape e' , e^2 , as shown in Fig. 5, in which tape e' , e^2 is ready to be knotted.

This suspensory, which is supported entirely at the front and solely in a vertical direction, once properly adjusted, never gets 110

out of place, at least in the positions most usually assumed by the wearer, such as standing, walking or sitting, and in no position whatsoever is there any pulling or 5 rubbing sensation felt at the groin, as so frequently happens with all suspensors having transverse support.

The comfort obtained with my improved suspensor is such that its wearer does not 10 realize that he has a suspensor on at all. This comfort is enhanced by the special cut of the main parts forming the pouch, and also because the front opening is not round, but oblong and quite high, as shown by the 15 line *w*, *x* Fig. 3. It is truly remarkable how the disposition of this opening frees the wearer from all irritation. A suspensor that stays in place, and leaves the wearer unaware that he has it on, must be acknowledged to be an ideal suspensor.

I claim and desire to obtain by Letters Patent the following:

1. A suspensor bandage comprising a waist band and a pouch having loops at 25 the top through which the waist band loosely passes, the loops being slideable along the waist band and tapes fastened to the waist band at each side of the front and adapted to be secured to the outside loops of 30 the pouch, whereby the pouch is suspended entirely at the front of the wearer and solely in a vertical direction.

2. A suspensor bandage comprising a waist band and a pouch having loops at the

top through which the waist band loosely 35 passes, the loops being slideable along the waist band and tapes fastened to the waist band at each side of the front and adapted to be secured to the outside loops of the pouch, whereby the pouch is suspended entirely 40 at the front of the wearer and solely in a vertical direction, said pouch having a vertically elongated front opening extending substantially to the top of the pouch.

3. A suspensor bandage comprising a 45 pouch having a vertically elongated front opening extending substantially to the top of the pouch, a band connected across the top of the pouch, vertical loops secured to said band, a waist band passing loosely 50 through said loops, the loops being slideable along the waist band, and tapes fastened to the waist band at each side of the front and adapted to be secured to the outside loops for limiting the longitudinal movement of 55 the loops on the waist band.

4. A suspensor bandage comprising a waist band, a pouch loosely supported from the waist band entirely at the front of the wearer and solely in a vertical direction, the 60 supporting means for said pouch having a limited sliding movement longitudinally of said waist band, and adjustable means for limiting said sliding movement.

JEAN MARIUS GARAIX.
